UNITED STATES PATENT OFFICE.

SAHATIEL G. MANDALIAN, OF NORTH ATTLEBORO, MASSACHUSETTS.

METHOD OF ORNAMENTING COAT-OF-MAIL MESH FABRIC.

Application filed June 24, 1924. Serial No. 721,996.

To all whom it may concern:

Be it known that I, SAHATIEL G. MANDALIAN, a citizen of the United States, residing at North Attleboro, in the county of 5 Bristol and State of Massachusetts, have invented certain new and useful Improvements in Methods of Ornamenting Coat-of-Mail Mesh Fabric, of which the following is a specification.

10 My invention relates to a method of applying enamel to the surface of a flexible fish scale or coat of mail metallic fabric employed in mesh bags and other ornamental articles of utility.

15 The essential objects of my invention are to apply liquid enamel to a fabric of the above character, and in such a manner as to impart thereto a mottled ornamental appearance; as well as to insure a permanency of such appearance.

20 To the above ends primarily my invention consists in such steps and in such successions of steps as fall within the scope of the appended claims.

25 In the accompanying drawings which form a part of this specification.

Figures 1 and 2 are a front elevation and a side elevation respectively of a piece of 30 coat of mail mesh fabric to be ornamented,

35 Figure 3 is a perspective of the mesh support,

Figure 4, a plan of the perforated figure plate,

Figure 5, a central transverse section of 35 the support, a piece of mesh carried therein, and the plate resting thereon,

Figure 6, a side elevation, partially in central section, of a pneumatic spraying device, and

40 Figure 7, a plan view of a portion of the ornamented sheet of mesh fabric.

Like characters of reference indicate like parts throughout the views.

45 The character of mesh fabric 10 desired to be ornamented is shown in Figures 1 and 2 and is a metallic mesh commonly known as "fish scale" or "coat of mail." It is extremely flexible and comprises parallel rows of thin metal ring links 11, each four of which links are engaged to a flat cruciform link or plate 12 by four corner prongs 13 converging at the rear of the plate. The constituent links of this fabric occupy 50 two different planes, and the shapes of the links are multiform, and their connection flexible which makes any su-

perficial ornamentation of the surface of the fabric a problem not heretofore successfully solved. My first step is to smooth or even the surface of the fabric and prevent derangement of the links during the subsequent steps. To effect this end it is convenient to employ the support 15 shown in Figures 3 and 5 consisting of a solid block or frame 15 having in its top a depression 17 of a depth equal to the thickness of the sheet 10 and of corresponding outline. In this depression the sheet is placed and its top face is flush with the top or shouldered surface 18 of the block. 60 Next is placed upon the block a metallic plate 20 shown in Figures 4 and 5. This rests or is clamped upon and in contact with the surface 18 and the sheet 10 as shown in Figure 5. This plate has circular holes or perforations 22 arranged in its body in series. The series of holes may extend over the entire area of the plate uniformly, or may be arranged to indicate a design of any shape. In Figure 4 the series of holes are arranged to indicate a simple design.

65 After the plate has been positioned as indicated a liquid enamel of any desired distinguishing color is by air projected in the form of a fine spray down against the perforated area of the plate. The portions 23 of the sheet 10 exposed through the holes 22 receive the spray impinging thereon through the latter as a multitude of spots. 70 When the surface under a particular hole is smooth a round spot is produced, as at 24 in Figure 7; but when such surface is broken, a broken effect is produced, as at 25. Thus the partially exposed area 23 has imparted thereto a generally mottled appearance. Experiment has demonstrated that the enamel must be applied in a spray form and that the spray be fine and forcibly projected. Further, that the plate 20 be of 75 substantial thickness.

80 A convenient means for producing and pneumatically applying the spray is the apparatus illustrated in Figure 6 wherein 27 is a covered non air tight vessel containing the liquid enamel and carrying a delivery pipe 29 terminating in a nozzle 31 extending laterally into a spraying mouth 32 of a nozzle 34 fast to the pipe 29 and supplied through a flexible pipe 36 with 85 air under pressure from a pump or other source of air supply. The air passing

through the nozzle 34 draws the enamel through the pipe 29 and forces it as a spray from the mouth 32. 37 is a handle, and 38 a thumb lever controlling the discharge of 5 the spray.

I claim:—

1. A method of imparting a mottled appearance to a metallic coat of mail fabric consisting in placing over the fabric to be treated a metallic plate provided with a series of holes, and injecting through the holes and into the interstices of the fabric a spray of liquid enamel.
2. A method of imparting a mottled appearance to a metallic coat of mail fabric consisting in placing over the fabric to be

treated a metallic plate provided with a series of holes and next injecting through the holes and into the interstices of the fabric by pneumatic means a spray of liquid 20 enamel.

3. A method of imparting a mottled appearance to a coat of mail fabric consisting in smoothing the fabric to be treated, next concealing the whole surface of the same except predetermined exposed spots, and finally projecting a spray of liquid enamel upon the exposed spots and through the interstices of the fabric.

In testimony whereof I have affixed my 30 signature.

SAHATIEL G. MANDALIAN.
